(57) **CLAIM**

The ornamental design for a ceiling fan, as shown and described.

DESCRIPTION

FIG. 1 is a top view of the ceiling fan in accordance with my design;

FIG. 2 is a bottom view of the ceiling fan in accordance with my design;

FIG. 3 is a side elevation view of the ceiling fan in accordance with my design;

FIG. 4 is a front elevation view of the ceiling fan in accordance with my design; and,

FIG. 5 is a top perspective view of one of the fans of the combination ceiling fan and light fixture shown separately for clarity of illustration.

The right and left side elevational views are mirror images of each other.

The front and back elevational views are mirror images of each other.

The down rod is shown broken away in FIGS. 3 and 4 to indicate indeterminate length.
